CHARLES M. HILSEE, OF PHILADELPHIA, PENNSYLVANIA, ASSIGNOR TO UNDERWOOD TYPEWRITER COMPANY, OF NEW YORK, N. Y., A CORPORATION OF DELAWARE.

TYPEWRITING MACHINE.

1,426,077.

Specification of Letters Patent. Patented Aug. 15, 1922.

Application filed December 24, 1917. Serial No. 208,543.

To all whom it may concern:

Be it known that I, CHARLES M. HILSEE, a citizen of the United States, residing in Philadelphia, in the county of Philadelphia and State of Pennsylvania, have invented 5 certain new and useful Improvements in Typewriting Machines, of which the following is a specification.

This invention relates to devices for collating sheets in typewriting machines, particularly those of the round platen variety; that is, in adjusting superposed sheets to the printing point in certain relations to one another, and further includes the method 10 involved.

One of the principal objects of the present invention is to provide means for expeditiously collating and bringing to printing position a statement, bill or item sheet, 20 and a ledger or other general record sheet.

An example of the classes of work to which this invention is adapted, is where each statement or bill is to contain an entry consisting of only a single line of typing, 25 but where it is desired to have these entries for successive days appear one under another upon the same record sheet.

The record sheet is first inserted around the platen and gaged longitudinally, and 30 then the statement sheet (which may be narrower than the record sheet) is inserted and brought to a predetermined relationship with the record sheet; whereupon by giving the platen a throw to a mechanically predetermined extent by means of a special 35 driver, both sheets are fed around to position to have the first line typed thereon.

The throw of the driver is regulatable step by step throughout a long range, so 40 that upon any day, after regulating the throw for that day, single-line entries may be entered upon a quantity of record sheets, one after another, without giving any further attention to positioning the record 45 sheet relatively to the printing point than merely to set it against the gage, and subsequently (after the insertion of a statement sheet) rotate the platen as far as it will go.

50 Other features and advantages will hereinafter appear.

In the accompanying drawings,

Figure 1 is a perspective front view of the platen frame or carriage of an Under-

wood typewriting machine with the present improvements applied thereto, in one form.

Figure 2 is a front view.

Figure 3 is a sectional side elevation.

The wide ledger sheet or other general record sheet 10 is introduced at its leading edge at the rear of the revoluble platen 11 and passed under the same and up in front thereof, and then adjusted or located endwise by means of a rear gage 12, up against which the trailing edge or bottom end of the sheet is backed. To facilitate such introduction and gaging of the sheet, there is employed a wide chute forming a paper-table or collating table mounted at the introductory side of the platen and comprising a floor 13 upon which the sheet lies, and sides 14 which confine or gage the sheet laterally. Said floor inclines downwardly and forwardly to converge to the platen, 70 and preferably curves forwardly under the platen, and said sides preferably extend entirely around the platen at 14°. The aforesaid gage 12 is preferably mounted upon the floor of the chute, in a manner to permit of adjustment to accommodate sheets of different length. Scales 15 may be provided upon the opposite sides of the chute for convenience in setting the gage, which may consist of a bar extending across the chute and having fastening screws 16 with shanks threaded down into nuts 17 fitting in slots 18 extending up and down the floor 13.

While the operator holds the ledger or record sheet adjusted to gage 12, he restores to effective positions the forward and rear feed rolls 19, 20, to press the ledger sheet 10 against the under side of the platen; the feed-roll release mechanism 21 usual in the Underwood typewriting machine, including a key 22, being employed for this purpose. If desired, spring clips 22a may hold the ledger sheet.

The ledger sheet 10 has not yet reached the position for receiving the first line of writing, but is temporarily retained in this preliminary position for the purpose of collating the statement or other item sheet relatively thereto. This statement sheet 23, 100 which is usually much narrower than the ledger sheet, may now be introduced (together with its carbon sheet 24) by the aid

of guides that are mounted at the introductory side of the platen and are in the nature of a narrow second chute placed between the rear of the platen and the floor 5 of the main chute, in spaced relation forwardly from the latter, so as to provide a clear space at its back for the ledger-sheet 10, or other work-sheets guided by the main or wide chute. The statement guide, 10 if used, may comprise gages 25 for the side edges of the statement, these gages being supported in any suitable manner, as by means of arms 26 extending inwardly towards each other from the sides 14 of the 15 main chute, to which said arms are fast. Preferably there are attached to these side guides floor portions 27 for directing the statement downwardly around the platen.

The statement 23 and its associated car- 20 bon 24 are laid upon these floors 27 between said gages 25 and thrust forwardly, around under the platen as far as the statement will go. Its leading edge is then presented to the bite of the rear feed roll 20 and the 25 platen, the roll thus serving as a stop or gage, against which the leading edge of the statement sheet is adjusted. The statement sheet is now in proper relationship with the record sheet, although neither one is in 30 position to receive the first line of typing.

From the described positions, the collated sheets are advanced by a continuous movement as a unit, to a predetermined typing position at the writing line, by sheet-driv- 35 ing means comprising a device which at a single stroke imparts a continuous forward rotation to the platen. This platen-rotating device or platen-driver comprises a handle 28 swinging loosely around the platen axle 40 29, and having a pawl 30 to engage a ratchet wheel 31 which is fixed to the platen axle; the stroke of the handle being limited by relatively adjustable stops 33, 33. By grasping the handle and turning the platen as 45 far as it will go, the operator is enabled, by a continuous movement at a single stroke, to advance both sheets as a unit exactly to the printing point, that is, with the first blank line thereon in register with the wing scales 50 34, which are usually mounted at the front of the platen.

It will be seen that by depression of the releasing key or device 22, the sheet-feeding platen is prevented from controlling the 55 sheet 10 while the latter is being introduced forwardly around the bottom of the platen; that by the use of the herein-described gag- 60 ing or positioning means at the introductory or near side of the platen, the work-sheets are collated (or arranged in mechanically determined, overlapping positions) at the same time that they are located where they may be advanced by the platen; that such collated work-sheets are advanced as a unit 65 by a mechanically limited operation of lever

28 precisely to the different typing posi- 70 tions that were predetermined by said pos- 75 titioning means; and that the sheets are there- 75 fore brought to typing positions by means of a succession of mechanically arrested in- 75 dividual and assembly movements thereof, whereby the desired facility, speed and ac- 75 curacy are secured.

The operator then types the entry, which 75 usually consists of one line, and removes the 75 sheets from the machine. The sheets are 75 usually kept together, preparatory to insert- 80 ing them on the succeeding day for receiv- 80 ing a fresh entry. In this manner the typ- 80 ing of ledger sheets and statements proceeds 80 until the day's entries are finished.

On the succeeding day the operator again 85 inserts each of the ledger sheets, one after 85 another, as before, against said gage, and in 85 each case also introduces the accompanying 85 statement sheet in the manner described.

But in order that the typing of each entry 90 that is made upon this succeeding day may fall below the typing of the preceding entry, on the statement and ledger sheets, the platen 90 is given one extra advance by means of said handle 28. In order to secure this extra 95 platen movement, either one or the other of the stops 33, 33 may be reset, so as to extend 95 the range of movement of said handle as far 95 as required. It will be understood that the extent of movement of said handle 28 may be thus increased an additional step prepara- 100 tory to performing each successive day's work, so that any item that is written upon 100 any day will fall just below the last written item.

The advantage is gained that the ledger 105 or other sheet, which it is desired to retain as a permanent record, receives the ink-rib- 105 bon impressions of the types, which are pref- 110 erable to the carbon impressions that are made upon the statement sheet. Moreover, the operation of collating and advancing the sheets is simple and mechanical, not requir- 110 ing the use of the eye or judgment of the operator, either to bring them into exact collated relationship with each other, or to advance them as a unit to the exact prede- 115 termined typing point at the writing line 115 on the platen of the typewriting machine; so that the operation of inserting and ad- 120 justing the sheets is very rapidly performed, and a great advantage is thus gained, espe- 120 cially where there is a large quantity of this single-line work to be performed.

The ledger sheet is usually much wider than the statement sheet, which, as at Figure 2, is preferably located about the middle of the ledger sheet, so that certain items may 125 be written upon the overlapping margins of the ledger sheet which it is not desired to have appear upon the statement.

The spring clips 22^a are attached to the rear-end gage 12 to be adjustable therewith. 130

They bear lightly upon the floor 13 of the chute, and are upturned at their free forward ends, and yield to the thrust of the sheet thereunder, so that by simply backing 5 up the sheet as far as it will go, the operator assures that the sheet will remain undisturbed in its gaged position until the feed rolls 19, 20, are restored. The spring clips 22^a preliminarily hold the gaged or 10 adjusted sheet in place while permitting it to be fed forward around the platen when the latter is rotated.

Variations may be resorted to within the scope of the invention, and portions of the 15 improvements may be used without others.

Having thus described my invention, I claim:

1. The combination of a revoluble platen, an introductory chute for said platen, including means for side-gaging the sheet, a gage for the rear ends of the sheet placed in said chute, side gages and a flooring forming a second guide for guiding a separate sheet, said second guide arranged between the 25 platen and said chute, arms projecting inwardly from the sides of said chute to support said side gages, and a feed roll to hold the sheet upon the platen, said roll serving as a gage for the leading end of a sheet introduced by means of said secondary guide.

2. The combination of a revoluble platen, an introductory chute for said platen, a gage for the rear ends of sheets placed in said chute, a clip for said sheets on said gage, 35 and a feed roll to hold the sheets upon the platen, said roll serving as a gage for the leading end of a second sheet introduced between the first sheet and the platen.

3. In a typewriter, the combination with 40 a revoluble platen, of means for variably gaging work-sheets to predetermined positions relative thereto and to each other for typing, said means including means for variably gaging one of said sheets by one end, a 45 clip to hold it in place when thus gaged, and means to gage another of said sheets by its opposite ends into a predetermined relationship with the first-mentioned sheet.

4. In a typewriter, the combination with 50 a revoluble platen, of means located at the introductory side of said platen for variably gaging work-sheets to predetermined positions relative thereto and to each other for typing, said means including means for 55 variably gaging one of said sheets by its trailing end, a clip to hold said sheet in place when thus gaged, and means to gage the other of said sheets by its leading edge into a predetermined relationship with the 60 first-mentioned sheet.

5. The combination with a revoluble platen, of an introductory chute for said platen having an open face to enable work-sheets to be laid therein, a gage for the rear 5 end of a sheet laid therein, means for de-

taining an adjusted sheet in said chute, a second open-faced chute at the introductory side of the platen adapted to guide a narrower work-sheet between the first work-sheet and the platen, an edge gage for each 70 chute, and feed-rolls for advancing the two work-sheets together.

6. The combination with a revoluble platen, of an introductory paper-feeding chute, open at the side facing said platen, to 75 enable a work-sheet to be laid therein, an adjustable end gage for the trailing end of said sheet, a scale to determine different positions of said end gage, means shiftable with said gage for detaining the adjusted 80 sheet in position, a second paper-feeding chute, also open at the side facing said platen, adapted to guide a narrower work-sheet between the first work-sheet and the platen, an edge gage for each chute, and 85 feed-rolls for advancing the two work-sheets together.

7. In a typewriting machine, the combination with a revoluble platen, of sheet-collating means at the introductory side of the 90 platen comprising a chute for receiving and guiding a work-sheet, a second chute at the introductory side of the platen forward from the first chute for receiving and guiding a work-sheet, an end gage carried by one of 95 said chutes for gaging the trailing edge of the work-sheet guided thereby, and an end gage at the introductory side of the platen for gaging the leading edge of the work-sheet guided by the other chute.

8. In a typewriting machine, the combination with a revoluble platen, of sheet-collating means at the introductory side of the platen comprising a wide chute for receiving and guiding a work-sheet, a narrow 105 chute at the introductory side of the platen forward from the wide chute in spaced relation thereto for receiving and guiding a work-sheet, an end gage at the introductory side of the platen for gaging the leading edge of the work-sheet guided by the narrow chute, and an end gage carried by 110 the wide chute for gaging the trailing edge of the work-sheet guided thereby.

9. In a typewriting machine, the combination with a revoluble platen, of sheet-collating means at the introductory side of the platen comprising a chute for receiving and guiding a work-sheet, a second chute at the introductory side of the platen forward 120 from the first chute for receiving and guiding a work-sheet, an adjustable end gage carried by one of said chutes for gaging the trailing edge of the work-sheet guided thereby, and a feed-roll for clamping the latter 125 work-sheet on the platen and forming an end gage for the leading edge of the work-sheet guided by the other chute.

10. In a typewriting machine, the combination with a revoluble platen, of sheet-col-

lating means at the introductory side of the platen comprising a wide chute for receiving and guiding a work-sheet, a narrow chute at the introductory side of the platen forward 5 from the wide chute in spaced relation thereto for receiving and guiding a work-sheet, an adjustable end gage carried by the wide chute for gaging the trailing edge of the work-sheet guided thereby, and a feed-roll 10 for clamping the latter work-sheet on the platen and forming an end gage for the leading edge of the work-sheet guided by the narrow chute.

11. In a typewriting machine, the combination with a revoluble platen, of sheet-collating means at the introductory side of the platen comprising a chute for receiving and guiding a work-sheet, a second chute at the introductory side of the platen forward 15 from the first chute in spaced relation thereto for receiving and guiding a work-sheet, an end gage carried by one of said chutes for gaging the trailing edge of the work-sheet guided thereby, an end gage at the 20 introductory side of the platen for gaging the leading edge of the work-sheet guided by the other chute, and sheet-holding means carried by said gage-carrying chute for detaining in adjusted position the work-sheet 25 guided thereby.

12. In a typewriting machine, the combination with a revoluble platen, of sheet-collating means at the introductory side of the platen comprising a chute for receiving and 30 guiding a work-sheet, a second chute at the introductory side of the platen forward from the first chute for receiving and guiding a work-sheet, an end gage carried by the first chute for gaging the trailing edge of the work-sheet guided thereby, an end gage at the introductory side of the platen for 35 gaging the leading edge of the work-sheet guided by the second chute, and sheet-holding means carried by the first chute for detaining in adjusted position the work-sheet 40 guided thereby.

13. In a typewriting machine, the combination with a revoluble platen, of sheet-collating means at the introductory side of the platen comprising a wide chute for receiving and 45 guiding a work-sheet, a narrow chute at the introductory side of the platen forward from the wide chute in spaced relation thereto for receiving and guiding a work-sheet, 50 an end gage at the introductory side of the platen for gaging the leading edge of the work-sheet guided by the narrow chute, an end gage carried by the wide chute for gaging the trailing edge of the work-sheet 55 guided thereby, and sheet-holding means carried by the wide chute for detaining in adjusted position the work-sheet guided thereby.

14. In a typewriting machine, the combination with a revoluble platen, of sheet-coll-

lating means at the introductory side of the platen comprising a chute for receiving and guiding a work-sheet, a second chute at the introductory side of the platen extending over and forward from the first chute in spaced relation thereto for receiving and guiding a work-sheet, an adjustable end gage carried by one of said chutes for gaging the trailing edge of the work-sheet guided thereby, a feed-roll for clamping the latter work-sheet on the platen and forming an end gage for the leading edge of the work-sheet guided by the other chute, and a spring-pressed clip carried by said gage-carrying chute for lightly pressing against the work-sheet guided thereby to hold the work-sheet in place while permitting it to be fed forward around the platen.

15. In a typewriting machine, the combination with a revoluble platen, of sheet-collating means at the introductory side of the platen comprising a chute for receiving and guiding a work-sheet, a second chute at the introductory side of the platen extending over and forward from the first chute for receiving and guiding a work-sheet, an adjustable end gage carried by the first chute for gaging the trailing edge of the work-sheet guided thereby, a feed-roll for clamping the latter work-sheet on the platen and 95 forming an end gage for the leading edge of the work-sheet guided by the second chute, and a spring-pressed clip carried by the first chute for lightly pressing against the work-sheet guided thereby to hold the work-sheet 100 in place while permitting it to be fed forward around the platen.

16. In a typewriting machine, the combination with a revoluble platen, of sheet-collating means at the introductory side of the platen comprising a wide chute for receiving and guiding a work-sheet, a narrow chute at the introductory side of the platen forward from the wide chute in spaced relation thereto for receiving and guiding a work-sheet, an adjustable end gage carried by the wide chute for gaging the trailing edge of the work-sheet guided thereby, a feed-roll for clamping the latter work-sheet on the platen and forming an end gage for the leading edge of the work-sheet guided by the narrow chute, and a spring-pressed clip carried by the wide chute for lightly pressing against the work-sheet guided thereby to hold the work-sheet in place while permitting it to be fed forward around the platen.

17. A front-strike typewriting machine having a revoluble sheet-feeding platen and having provision for locating different sheets, by a succession of mechanically arrested individual and assembly movements thereof, in such superposed relation at the printing point that the typing falls in different predetermined locations on the dif- 125 ferent 130

ferent sheets, comprising (1) a releasing device for rendering the platen unable to control a sheet while being introduced around the same, (2) positioning means at 5 the introductory side of the platen by the use of which the work-sheets, as they are introduced at the rear side of the platen in position to be advanced thereby, may be collated or arranged in mechanically determined 10 overlapping positions, and also comprising (3) means co-operating with said platen and effective to advance by a mechanically limited operation such collated work-sheets as a unit precisely to the 15 different typing positions predetermined by said positioning means.

18. A front-strike writing machine having a revoluble platen, and having releasable means to bear upon the platen for feeding 20 to typing position work-sheets collated at the introductory side of the platen, said machine having provision for gaging or collating one work-sheet by its trailing end and provision for collating another work- 25 sheet differently by its leading end, as the sheets are introduced one by one in feeding relation to the platen, said machine also having means effective, by a mechanically limited operation, to co-operate with said 30 platen and said feeding means for advancing the collated sheets as a unit to predetermined typing positions.

19. In a front-strike typewriting machine, the combination with a revoluble 35 platen and a releasable feed-roll to run upon the platen at its introductory side, of a gage effective to locate the trailing end of a work-sheet which occupies a position between said platen and said feed-roll, said 40 roll usable as a gage for the leading end of a different work-sheet inserted between the first work-sheet and the platen, and means having a mechanically limited operation for co-operating with the platen 45 and feed-roll to advance the collated sheets as a unit for a predetermined extent from their original positions to bring them to typing positions predetermined by said gage and said roll.

50 20. In a typewriting machine, the combination with a revoluble platen, of a chute at the introductory side of the platen for receiving and guiding a work-sheet to the platen, a second chute at the introductory 55 side of the platen forward from the first chute for receiving and guiding a work-sheet to the platen, an end gage carried by one of said chutes for gaging the trailing edge of the work-sheet guided thereby while 60 the leading end of the work-sheet passes into position to be gripped by the platen, an end gage at the introductory side of the platen for gaging the leading edge of the work-sheet guided by the other chute, where- 65 by said work-sheets may be collated, and

a platen-driver for advancing by a mechanically limited operation the collated work-sheets as a unit to typing position.

21. In a typewriting machine, the combination with a revoluble platen, of a chute 70 at the introductory side of the platen for receiving and guiding a work-sheet to the platen, an end gage for gaging the trailing edge of the work-sheet guided by the chute while the leading end of the work-sheet 75 extends under the platen to position to be gripped against the same, an end gage at the introductory side of the platen for gaging the leading edge of a second work-sheet inserted between the first work-sheet 80 and the platen, whereby said work-sheets may be collated relatively to each other and to the platen, and sheet-driving means for advancing by a continuous movement at a single mechanically limited stroke the collated work-sheets as a unit to a predetermined 85 typing position at the writing line on the platen.

22. In a typewriting machine, the combination with a revoluble platen, of a chute 90 at the introductory side of the platen for receiving and guiding a work-sheet to the platen, an end gage for gaging the trailing edge of the work-sheet guided by the chute while the leading end of the work-sheet 95 extends under the platen to position to be gripped by the same, a releasable feed-roll for clamping said work-sheet on the platen and forming an end gage for the leading edge of another work-sheet inserted 100 between the first work-sheet and the platen, whereby said work-sheets may be collated relatively to each other and to the platen, a driver for advancing as a unit the collated work-sheets by a continuous movement at a single mechanically limited stroke 105 of said driver to a predetermined typing position, and adjustable means for regulating the stroke of said driver.

23. The method of positioning a plurality 110 of different kinds of work-sheets in a typewriting machine, for simultaneously typing the same entries on such different kinds of work-sheets, which consists in gaging a work-sheet of one kind by its trailing edge 115 at the introductory side of the typewriter platen, gaging a work-sheet of another kind by its leading edge at the introductory side of the platen into a predetermined collated relationship with the first sheet, and then 120 by a single continuous movement advancing the collated work-sheets as a unit to a mechanically predetermined typing position at the writing line on the platen of the typewriting machine.

24. The method of producing from time to time the same succession of entries on a plurality of different kinds of work-sheets which consists in gaging a work-sheet of one kind by its trailing edge at the intro- 130

ductory side of a typewriter platen, gaging a work-sheet of another kind by its leading edge at the introductory side of the platen into a predetermined collated relationship with the first work-sheet, by a single continuous movement advancing the collated work-sheets as a unit to a mechanically predetermined typing position at the writing line on the platen of the typewriter, typing an entry on the collated and positioned work-sheets, and re-

moving the typed work-sheets from the machine; then repeating the above-noted procedure, but each time by a single continuous movement advancing the collated work-sheets as a unit to a new mechanically predetermined typing position next following the last preceding typed entry. 15
